UNITED STATES PATENT OFFICE.

GERHARD ROTHMANN, OF HERNE, GERMANY.

PORTABLE COMPRESSOR PLANT.

Application filed April 9, 1928, Serial No. 268,555, and in Germany July 8, 1926.

The object of my present invention is to produce a portable compressor-plant for the production of compressed air similar to those now employed for the construction of roads, 5 railway-tunnels, galleries of mines and similar structural work. My improved compressor-plant is more especially designated for the operation of concrete-breakers, rock-drills and the like. Compressor-plants of this 10 type as a rule consist of a two- or of a four-wheeled carriage or truck, on which the compressor is arranged and driven by an internal combustion-engine or by an electric motor. Hitherto such portable plants for the production of compressed air were not equipped 15 with a particular device for cooling the newly compressed and highly heated air for which reason the rubber-hose employed to convey it to a working tool or machine is very injurious- 20 ly influenced and the lubricating oil carried away and held in suspension by said compressed air can not be completely removed. In stationary compressor-plants these disadvantages do not appear and for this very reason 25 an especial cooling of the air is not required, since it is possible to employ a storage tank of such large dimensions that on this account alone a sufficient cooling of the compressed air is obtained before it is used; 30 whereas in portable compressor-plants a cooling of the compressed air worth mentioning is impossible on account of the small dimensions of the air storage-tank permitted by the restricted space at disposal in such cases. 35 In accordance with my present invention the highly heated compressed air is fully cooled on its way from the compressor to the storage-tank and to this end it is passed through an air-cooler arranged in the current 40 of air created by the ventilator provided for the operation of the water-cooler which supplies the necessary cooling water to the cylinder of the motor or to the cylinder of the compressor, or to both, in order to not only 45 obtain the cooling of the compressed air but simultaneously therewith the condensation and separation of the vapours of the lubricating-oil held in suspension therein.

Although it is known to employ in compressor-plants two coolers arranged one behind the other in the air current of a ventilator, this arrangement simply represents a division of a primary cooler originally intended to provide on the one hand the motor-cylinder and on the other hand the compressor-cylinder with cooling-water. It is also known to provide automobiles and other power-vehicles with an auxiliary compressor in order to obtain the final or maximum compression of the combustion-air and thereby let the 60 fully compressed air pass through a cooler arranged at the front-end of the vehicle beneath the water-cooler of the motor in such a manner that the cooling of the water is accomplished by the draft of the air created 65 during the forward motion of the onward speeding vehicle.

It is expedient to arrange the air-cooler in the air-current created by the ventilator in front of and adjacent to the water-cooler of 70 the motor and to dimension it with a view to approximately cover the front of the water-cooler. In this way it is possible to obtain the further advantage that the novel air-cooler protects the water-cooler of the motor 75 against mechanical damages.

In the accompanying drawing an embodiment of my present invention is shown by way of example, wherein:—

Figure 1 is a side elevation of a partially 80 diagrammatically represented portable compressor-plant in accordance with my present invention, and

Figure 2 is a front elevation of said plant. Upon the carriage 1, adapted to be moved 85 along by animal power in the direction of the arrow 1', an air-compressor 2 is arranged and operated by an internal combustion-engine 3 only diagrammatically indicated like the compressor 2. This internal combustion-engine may, of course, be replaced by an electric motor when electric power is obtainable. In front of the water-cooler 4, which furnishes the cooling water to the compressor 2 and to the motor or combustion-engine 3 by means of 90 a pipe 5 provided with stop-cocks 5', as indicated in Figure 1, an air-cooler C is arranged in the current of air created by a ventilator or fan 6 and forced by the latter through said water-cooler. To this air-cooler the air compressed in the compressor 2 and introduced by the latter in a highly heated condition into the head or helmet 7 of the compressor, is directed by a pipe 8 attached by a flanged connection 9 to the bottom pipe 10 of said 105 air-cooler. This pipe is subdivided by an intermediate wall 11 whereby an inlet division 12 and an outlet division 13 are formed of which the former is connected with a condensate-collector 14 and the latter with a 110 similar condensate-collector 15. Upon the condensate-collector 14 a capped ascension-

pipe 16 is arranged and connected by means of a plurality of horizontally arranged intermediate pipes 17 with a correspondingly shaped descension-pipe 18 carried by the condensate-collector 15. By the arrangement of pipes indicated above a comparatively flat structure of approximately the same area as the front of said water-cooler is obtained. This structure may be built up of castings or produced in any other suitable way.

After the compressed air has passed from the compressor helmet 7 through the pipe 8 and the several parts of the air-cooler C to the outlet division 13 it has lost its heat under the action of the air-current forced by the ventilator through the water-cooler 4 and consecutively utilized for cooling the tubular elements of the upper part of the air-cooler C. When the cooled compressed air has reached the outlet-division 13 it passes through a branch-pipe 19 into a storage-tank 20 of cylindrical shape, as indicated in Figure 1. This tank is provided with a cock 21 which controls a nozzle 22 of the usual shape for the attachment of a rubber hose or a flexible pipe (not shown) by means of which the cooled compressed air is conveyed to a suitable tool. Since the action of the air current created by the ventilator is very effective a second and very important advantage is simultaneously obtained thereby which consists in the condensation of the vapours of the lubricating-oil contained and carried along by the compressed air when introduced into the air-cooler C. The condensate of the condensated vapours flows into the condensate-collectors 14 and 15 and is removed therefrom by the aid of pet-cocks 23. To regain the lubricating oil from the compressed air in this manner is more productive and more easily accomplished than by purely mechanical means. Besides this the novel air-cooler C offers by means of the arrangement of its pipes a very effective protection against mechanical damages to the water-cooler 4 arranged just behind it.

I claim:—

1. A portable compressor-plant comprising an air-compressor, a motor for operating said air-compressor, a water-cooler, a ventilator for creating a current of air for cooling the contents of said water-cooler, an air-cooler arranged in the current of air created by said ventilator, means for leading the heated compressed air from said air-compressor to said air-cooler destined to cool said air and condense the oil-vapours suspended therein, and a storage-tank for the cooled compressed air.
2. A portable compressor-plant comprising, an air-compressor, an internal combustion-engine for operating said air-compressor, a water-cooler, a ventilator for creating a current of air adapted to cool the contents of said water-cooler, an air-cooler ar-

ranged in said current of air and mounted in front of said water-cooler; a tubular channel for leading the heated compressed air from said air-compressor to said air-cooler destined to cool said air, condense the oil-vapours suspended therein and deposit the resulting condensate; and a storage-tank for the cooled and purified compressed air.

3. A portable compressor-plant comprising, an air-compressor, a motor for operating said air-compressor, a water-cooler, a ventilator for creating a current of air adapted to cool the contents of said water-cooler, an air-cooler arranged in said current of air in advance of said water-cooler and composed of tubular elements united to form a flat structure of approximately the same area as the front of said water-cooler, condensate-collectors arranged at the lower end of said air-cooler, tubular means for transferring the heated compressed air from said air-compressor to said air-cooler destined to cool said air, condense simultaneously therewith the oil-vapours suspended in it and retain the condensate by said collectors, and a storage-tank for the cooled and purified compressed air.

4. A portable compressor-plant comprising an air-compressor, a motor for operating said air-compressor, a water-cooler, a ventilator for creating a current of air adapted to cool the contents of said water-cooler; an air-cooler arranged in said current of air in front of said water-cooler and composed of a vertical ascension-pipe, a vertical descension-pipe, a plurality of intermediate pipes connected with said vertical pipes to form a flat structure of an areal extent approximately equalling that of the front of said water-cooler, condensate-collectors carried by said vertical pipes, a bottom-pipe arranged between said condensate-collectors and provided with a division-wall adapted to direct the flow of air through said air-cooler; means for introducing the heated compressed air into said bottom-pipe at one side of said division-wall whence it passes through said air-cooler to the other side of said division-wall, and a storage-tank for the cooled and purified compressed air.

5. A portable plant for producing compressed air comprising a compressor; an internal combustion engine for driving said compressor; means for cooling said internal combustion engine including a fan; a storage tank for the compressed air; and an air cooler for cooling the compressed air before it enters the tank, said cooler cooperating with the fan so that the air driven by the fan will cool the compressed air in the cooler.

6. A portable plant for producing compressed air comprising a water-cooled compressor; a water-cooled internal combustion engine; a radiator for the water of the compressor and the internal combustion engine;

- 5 a fan for cooling the water in the radiator; a storage tank for the compressed air; and an air cooler arranged adjacent the radiator for cooling the compressed air before it enters
5 the tank, the compressed air in the cooler being cooled by the air drawn by the fan through the radiator.
7. A portable plant for producing compressed air comprising a compressor; an internal combustion engine for driving said compressor; means for cooling said internal combustion engine including a fan; and an air cooler for cooling the compressed air, said cooler cooperating with said fan so that
10 the air driven by the fan will cool the compressed air in the cooler.
8. A portable plant for producing compressed air comprising a compressor; an internal combustion engine for driving said compressor; means for cooling said internal combustion engine; and a cooler for cooling the compressed air, said cooler cooperating with said means to also cool the compressed air.
9. A portable plant for producing compressed air comprising a compressor; means for cooling said compressor; and a cooler for cooling the compressed air, said cooler cooperating with said means to also cool the compressed air.

In testimony whereof I affix my signature.
GERHARD ROTHMANN.
